ABSTRACT OF THE DISCLOSURE

The enzymes present in an enzyme-bearing detergent composition are stabilized by small amounts of N-acyl amino acids whose acyl groups are derived from saturated or unsaturated fatty acids having 6 to 20 carbon atoms, and the enzymes are also stable in detergents in which the N-acyl amino acids are the primary surfactant ingredients.

This invention relates to detergent compositions, and particularly to improved enzyme-bearing detergent compositions.

Enzyme-bearing detergent compositions have recently found wide application. In addition to the enzyme, such compositions may typically contain an anionic surfactant as the primary active ingredient, such builders as sodium tripolyphosphate, sodium silicate, Glauber's salt, and addition agents such as carboxymethylcellulose, optical brightening agents, dyes, perfumes, etc.

The known compositions suffer from the fact that the anionic surfactants make the enzymes unstable. The alkaline builders inactivate the enzymes at temperatures of 40° C. or more. The enzymes are even less stable in aqueous solutions having a pH of 10–11 as normally caused by the other ingredients of the conventional compositions.

A practically useful detergent composition in which the enzyme component is not significantly inactivated has not been available heretofore, and it is an object of this invention to provide an enzyme-bearing detergent composition wherein the enzyme is relatively stable.

It has now been found that the stability of the enzyme in detergent compositions of the type described is enhanced by the presence of an N-acyl amino acid, and its salts and esters, the N-acyl group being the radical of a fatty acid having 6–20 carbon atoms. The stabilizing agents of the invention are effective both in aqueous solutions and in dry detergent powders. The stabilizing agents of the invention will be referred to hereinafter as "N-higher acyl amino acids" for the sake of brevity.

To demonstrate the effectiveness of the stabilizing agents, two detergent bases were prepared. Base A consisted of 25% sodium n-dodecylbenzene sulfonate, 30% sodium tripolyphosphate, 5% sodium metasilicate, 37% Glauber's salt, and 3% carboxymethylcellulose together with 0.1% protease (60,000 units/g. as determined by the modified Anson method described hereinbelow). Base B differed from Base A by substitution of sodium lauryl sulfate for the sodium n-dodecylbenzene sulfonate.

Aqueous 2% solutions of the bases having a pH of 10 were mixed with the N-higher acyl amino acids listed in Table 1 in a concentration of 0.2%, each mixture was heated to 50° C. for 30 minutes, and the residual enzyme activity was measured. The term "hydrogenated tallowyl" is used in this specification for brevity's sake for the acyl radicals of the fatty acids in hydrogenated beef tallow. The term "cocoyl" will be used in an analogous manner.

In respective control tests, no N-higher acyl amino acid was added.

As is evident from Table 1, the stabilizing agents of the invention sharply reduce the loss of enzyme activity under the test conditions.

TABLE 1

Expt. No.	N-higher acyl amino acid	Rate of residual activity, percent	
		Deter- gent base [A]	Deter- gent base [B]
10	None	10	20
1	N-caproyl-L-valine	28	25

21	N-undecylenoyl-L-valine	26	40
22	N-lauroyl-L-aspartic acid	33	35
23	N-palmitoyl-L-aspartic acid	37	45
24	N-palmitoyl-L-asparagine	29	30
25	N-palmitoyl-DL-homocysteic acid	32	31
26	N-hydrogenated tallowyl-glutamic acid	36	35
27	N-lauroyl-L-arginine	48	55
28	N-palmitoyl-L-arginine	38	58
29	N-hydrogenated tallowyl-L-arginine	50	36
30	N-lauroyl-L-arginine methyl ester	25	38
31	N-lauroyl-L-ornithine methyl ester	49	62
32	N,N-dimethyl-N-lauroyl-L-ornithine	55	65
33	N-palmitoyl-L-lysine methyl ester	54	60
34	N-hydrogenated tallowyl-L-arginine	54	55
35	N-palmitoyl-L-lysine methyl ester	37	43
36	N-stearoyl-L-serine		

Detergent bases A and B were modified to contain 0.4% protease, and batches of the modified bases were further mixed with the stabilizing agents of the invention listed in Table 2 in amounts of 0.8%. The powder compositions so obtained were stored at 84% relative humidity and 37° C. in a desiccator over saturated aqueous ammonium chloride solution for 7 and 14 days together with controls free from the N-higher acyl amino acids, and the residual enzyme activity was determined in percent of the initial value. The improved shelf life of the compositions according to this invention is evident from Table 2.

TABLE 2

Expt. No.	N-higher acyl amino acid	Rate of residual activity, percent			
		Detergent base [A]	7 days	14 days	Detergent base [B]
55	None	62	40	85	65
37	N-lauroyl-L-arginine methyl ester hydrochloride	84	64	94	82
38	Sodium N-hydrogenated tallowyl-L-glutamate	100	100	98	95
39	N-palmitoyl-L-valine	94	90	100	92

The N-higher acyl amino acids of the invention also favorably affect the cleaning efficiency of detergent compositions containing enzymes.

Samples of cotton fabric artificially soiled (Empa 116) were soaked in a liquor ratio of 1:50 in aqueous 0.2% solutions of detergent base A without protease, with 0.001% protease (60,000 u./g.) but without N-higher acyl amino acid and with 0.001% protease and varying

amounts of N-palmitoyl valine (P-V) or sodium N-hydrogenated tallowyl-L-glutamate (HGS). After 10 minutes agitation at 100 r.p.m. at 30° C., the washed fabric samples were dried, and the rate of reflection L after washing was compared with the rate of reflection L' before washing on a color-difference meter with Hunter Standard (91.8). Cleaning efficiency CE (percent) was calculated according to the formula

$$CE = \frac{L - L'}{91.8 - L'} \times 100$$

The results obtained with the several detergent compositions are listed in Table 3.

TABLE 3

Expt. No.	41	42	43	44	45	46	47	48	49

CE, percent	60	68	71	67	69	69	67	73	73

The amount of N-higher acyl amino acid which stabilizes the enzyme in a detergent composition may be 0.1 to 20% based on the weight of the detergent base or 20% to 1000% based on the enzyme. The effects of varying amounts of N-palmitoyl valine (P-V) and sodium n-hydrogenated tallowyl-L-glutamate (HGS) on the residual activity of 0.01% protease in an aqueous 2% solution of detergent base A after 10 minutes at 50° C. is evident from Table 4.

Detergent compositions of the invention may be powders, granules, pastes, or liquids. The stabilizers of the invention may be used to advantage in heavy-duty synthetic detergent compositions containing alkaline builder or in light-duty synthetic detergent compositions without alkaline builder whose predominant detergent agent is an anionic, cationic, or nonionic surfactant.

The N-higher acyl amino acids themselves have excellent surface activity and are stable in hard water. They may be used, therefore, as predominant active ingredients in detergent compositions which may further contain enzymes with or without builders. In such compositions, the enzymes are very stable.

When N-higher acyl amino acids constitute the primary surfactant in enzyme bearing compositions, other synthetic surfactants and builders may also be present. Good detergency and foaming ability are achieved even in hard water without the use of alkaline builders, such as sodium tripolyphosphate and sodium silicate, and the solutions prepared from such compositions may be neutral or only slightly alkaline so as to further enhance the stability of the enzyme.

The results of comparison tests between various detergent compositions respectively containing protease, amylase (10,000 u./g. from *B. subtilis*), and lipase (20,000 u./g.) as shown in Tables 5, 6, and 7 together with controls. Cleaning efficiency was determined in the manner described with reference to Table 3 after 10 minutes and 30 minutes laundering. The residual enzyme activity was determined at ten times the concentrations indicated in the tables after 30 minutes heating to 50° C. (protease) or 40° C. (amylase, lipase). Protease activity was determined by the modified Anson method in which casein is used as the substrate, and 1 unit is the amount of protease which liberates 1 µg. equivalent of tyrosine per minute at 37° C. Amylase activity was determined by the modified Wohlgemuth method in which 1 amylase unit is the amount of enzyme which reduces the iodine color of 1 ml. of 0.65% soluble starch solution to an absorbance of 0.300 at 660 mµ in 10 minutes at 40° C. Lipase activity

was determined by the method of Yamada et al. [J. Agric. Chem. Soc. Japan 36 (1962) 860], one unit being the amount of enzyme liberating 1 µ equivalent of acid per minute.

The acyl groups of the N-higher acyl amino acids in the detergent compositions of the invention are those of saturated or unsaturated fatty acids having 6 to 20 carbon atoms, such as caproic, lauric, tridecanoic, decanoic, myristic, pentadecanoic, palmitic, margaric, stearic, and oleic acid, also of the fatty acid mixtures obtained from fats and oils, such as coconut oil, tallow oil, hydrogenated tallow oil, olive oil, soybean oil, corn oil, and the like.

The N-higher acyl amino acids may be used also in the form of their salts with alkali metals (sodium, potassium) or ammonium, with water soluble amines, particularly alkanolamines (mono-, di-, or triethanolamine) and triethylamine, with basic amino acids if the acyl group is attached to an acidic amino acid, or in the form of their acid addition salts with mineral acids (hydrochloric or sulfuric), organic acids (acetic acid, lactic acid, acidic amino acids if the acyl group is attached to a basic amino acid).

The amino acid moiety of the N-higher acyl amino acid may be an acidic amino acid (such as glutamic acid, aspartic acid, homocysteic acid, cysteic acid, amino adipic acid), a basic amino acid (such as lysine, arginine, ornithine, oxylysine, diaminobutyric acid, histidine, isolysine), or a neutral amino acid (such as glycine, alanine, valine, serine, proline, leucine, isoleucine, oxyproline, methionine, phenylalanine, threonine, tryptophane, cysteine, cystine, tyrosine, norvaline, norleucine, aminobutyric acid, amino-isobutyric acid, diaminopimelic acid, diaminooxypimelic acid, pantamine, taurine, aminovaleric acid, and amino-caproic acid). It may be optically active or racemic.

The N-methyl-N-acyl and N-ethyl-N-acyl derivatives of these acids also may be used, such as N-acyl derivatives of N-methylleucine, N-methylglycine, N-methylalanine, dimethyl ornithine, and also N-acyl peptide derivatives.

When the N-higher acyl amino acids of the invention are used in the form of esters, the esters may be the lower alkyl esters (methyl, ethyl, propyl, butyl) or higher alkyl esters (such as octyl, lauryl esters).

Alkaline or neutral protease, amylase, and lipase may be used in the detergent compositions of the invention singly or in mixtures of two or more.

If a synthetic surfactant is used as the predominant detergent component, it may be an alkyl benzene sulfonate, the sulfate of a higher alcohol or of an alkyl ethoxy ether, an α -olefin sulfonate, another alkylaryl sulfonate, a polyoxyethylene alkylphenyl ether, and may be mixed with a builder, other auxiliary agents (optical bleach, perfume, dye, CMC to prevent redeposition), the N-higher acyl amino acid, and the enzyme.

If the N-higher acyl amino acid is the sole or predominant surfactant, it may be combined with a builder, auxiliary agents, and the enzyme. The detergent composition in either case may be in the form of a powder, a shaped solid body, a paste, granules, a cream, an emulsion, or a solution, as may be required.

The detergent compositions of the invention have a long shelf life because of the stabilizing effect of the N-higher acyl amino acids on the enzymes, and only little of the enzyme activity is lost during use. Detergency is adequate, because the N-higher acyl amino acids are equal or superior in this respect to conventional detergents with which they are fully compatible.

When the N-higher acyl amino acids constitute the predominant active agent in a detergent composition, the composition has excellent stability and detergency in hard water without need for alkaline builders which impair enzyme activity. The solutions are neutral or weakly alkaline so that enzymes not suitable for alkaline solutions may be employed singly or in mixtures. The solutions may be employed for degreasing wool, as hair shampoos, and as detergents for kitchen use. The N-higher acyl amino acids tend to protect the skin and rarely cause irritation. They also have antibacterial or bacteriostatic effects.

The detergent compositions of the present invention may therefore be formulated as laundry detergents, for general kitchen use, for use in automatic dish washers, as shampoos, bar soaps, cleaning creams, tooth pastes, and for industrial use.

The following examples illustrate the preparation of detergent compositions of the invention.

Example 1

10 100 litre of water was added to a mixture of 2.5 kg. of sodium-n-dodecylbenzene sulfonate, 2.5 kg. of disodium N-hydrogenated tallowyl-DL-glutamate, 6 kg. of sodium tripoly-phosphate, 1 kg. of sodium metasilicate, 7 kg. of Glauber's salt and 0.6 kg. of carboxymethylcellulose, and the solution was spray-dried to obtain 18 kg. of white granular detergent. Laundry detergent was prepared by uniformly mixing the above granular detergent with 360 g. of granular protease.

Example 2

20 Powder laundry detergent was prepared by adding 12 g. of protease to a mixture of 250 g. of sodium N-hydrogenated tallowyl-L-glutamate and 5 g. of N-lauroyl-L-ornithine lauryl ester acetate.

Example 3

25 Laundry detergent was prepared by mixing 300 g. of the commercial laundry detergent, "Tide" (trade name, produced by The Procter & Gamble Company) with 6 g. of granular protease and 10 g. of dipotassium N-lauroyl-DL-aspartate.

Example 4

30 To a mixture of 500 g. of sodium lauryl sulfate, 10 g. of sodium N-palmitoyl-L-valine, 1.4 kg. of Glauber's salt and 50 g. of carboxymethylcellulose, 2 g. of optical whitening agent was added and thereafter 24 g. of powder from protease to obtain neutral laundry detergent in powder.

Example 5

35 50 g. of protease was mixed with a mixture of 3 kg. of sodium N-cocoyl-L-glutamate and 7 kg. of Glauber's salt. The obtained mixture was dissolved in water to make 60 litres and spray-dried to produce neutral laundry detergent for wool and synthetic fibers.

Example 6

40 50 g. of triethanolamine lauryl sulfate, 10 g. of diethanolamide of lauric acid, 10 g. of N-lauroyl-L-isoleucine monoethanolamine salt and a small amount of perfume were dissolved in water. 0.3 g. of protease and 1 g. of lipase were added thereto to prepare 300 g. paste shampoo composition.

45 The monoethanolamine salt was obtained by acylating a mixture of 60% L-leucine, 30% L-isoleucine, L-valine, L-alanine, L-threonine and L-methionine to the N-lauroyl derivatives, and by converting the same to the monoethanolamine salts.

Example 7

50 60 Deodorant cleaning cream was obtained by adding 0.1 g. of protease and a very small amount of perfume to a mixture of 35 g. of mineral oil, 12 g. of spermaceti, 2 g. of beeswax, 5 g. of N-lauroyl-L-arginine methyl ester DL- α -pyrrolidone-carboxylate, 2 g. of glycerin and 40 g. of water.

Example 8

65 70 Detergent for automatic dish washers was obtained by mixing 100 g. of ammonium N-tallowyl-D-glutamate, 1 g. of protease, 3 g. of lipase and 5 g. of amylase.

Example 9

75 Detergent for kitchen use was obtained by dissolving 5 g. of potassium N-lauroyl-DL-alaninate and 0.5 g. of protease in 200 g. of a commercial detergent for kitchen and Fats Co., Ltd.).

7
Example 10

A liquid dish washing detergent was obtained by adding 0.1 g. of protease and 1 g. of amylase to a mixture of 15 g. of lauryl alcohol ether sulfate, 10 g. of alkylamide of coconut fatty acid, 5 g. of ethyl alcohol and 2 g. of N-myristoyl-L-arginine butyl ester lactate.

What we claim is:

1. A detergent composition consisting essentially of an anionic synthetic surfactant, at least one enzyme selected from the group consisting of protease, lipase, and amylase, and an N-acyl amino acid, the amount of said surfactant being sufficient to make said enzyme unstable in the absence of said N-acyl amino acid, and the amount of said N-acyl amino acid being sufficient to enhance the stability of said enzyme in the presence of said surfactant, the acyl group in the N-acyl moiety of said N-acyl amino acid being the acid radical of a fatty acid having 6 to 20 carbon atoms, the nitrogen of said N-acyl moiety being bound to the carbon chain in the amino acid moiety of said N-acyl amino acid.

2. A composition as set forth in claim 1, wherein the remainder of said composition essentially consists of at least one builder selected from the group consisting of sodium tripolyphosphate, sodium metasilicate, and Glau-
25 ber's salt.

3. A composition as set forth in claim 1, wherein said N-acyl amino acid is an N-acyl derivative of an amino acid selected from the group consisting of glutamic acid, aspartic acid, homocysteic acid, cysteic acid, amino adipic acid, lysine, arginine, ornithine, oxylysine, diaminobutyric acid, histidine, isolysine, glycine, alanine, valine, serine,

8

proline, leucine, isoleucine, oxyproline, methionine, phenylalanine, threonine, tryptophane, cystein, cystine, tyrosine, norvaline, norleucine, aminobutyric acid, aminoisobutyric acid, diaminopimelic acid, diaminooxypimelic acid, pantonine, taurine, aminovaleric acid, aminocaproic acid, and sarcosine.

4. A composition as set forth in claim 1, wherein said N-acyl amino acid is an N-acyl derivative of an alpha-amino, beta-amino, or omega-amino acid.

5. A composition as set forth in claim 1, wherein said N-acyl amino acid is in the form of a sodium, potassium, or ammonium salt thereof or in the form of an alkyl ester thereof, said alkyl having up to 12 carbon atoms.

6. A composition as set forth in claim 1, the amount of said N-acyl amino acid being between 20% and 1000% of the amount of said enzyme.

7. A composition as set forth in claim 2, said builder being alkaline.
